UNITED STATES PATENT OFFICE.

RALPH WILLIAMS AND CHARLES S. BUSHELL, OF BELOIT, WISCONSIN.

BAND-SAW-FILING MACHINE.

1,186,357.

Specification of Letters Patent.

Patented June 6, 1916.

Application filed June 1, 1915. Serial No. 31,528.

To all whom it may concern:

Be it known that we, RALPH WILLIAMS and CHARLES S. BUSHELL, citizens of the United States, residing at Beloit, in the county of Rock and State of Wisconsin, have invented certain new and useful Improvements in Band-Saw-Filing Machines; and we do declare the following to be a full, clear, and exact description of the invention, such as will enable others skilled in the art to which it appertains to make and use the same.

Our invention relates to improvements in saw filing machines, and more particularly to those designed for filing band saws without removing the same from the machine.

The object of the invention is to improve upon the general construction of device of this class to the extent hereinafter described and pointed out in the claims.

In describing the invention, we shall refer to the accompanying drawings wherein like reference characters designate corresponding parts throughout the various views, and wherein:

Figure 1 is a front elevation of a saw filing machine constructed in accordance with our invention. Fig. 2 is a top plan view thereof. Fig. 3 is a rear side elevation. Fig. 4 and Fig. 5 are horizontal sectional views as seen respectively along the planes indicated by the lines 4-4 and 5-5 of Fig. 1. Fig. 6 is a detail vertical longitudinal section taken on the line 6-6 of Fig. 5. Figs. 7, 8 and 9 are vertical transverse sections taken respectively on the lines 7-7, 8-8 and 9-9 of Fig. 1. Fig. 10 is a perspective view of the sectional reciprocatory file operating rod. Fig. 11 is a detail horizontal section showing more particularly the construction of one of the filing clamps.

In these drawings, constituting a part of the application, 1 designates a T-shaped base having a shank 2 which is provided with a longitudinal slot 3 for the reception of a clamp (not shown), whereby the base may be secured to the table of a band saw. The head 4 of the T-shaped base 1 is here shown as provided with an upright centering screw 5 which is alined with the slot 3 and which is adapted to be projected into the slot of the aforesaid table to correctly position the base in respect to the saw S, after the clamp has been disposed in the slot of the table and the aforesaid slot 3.

Rising from the edge of the head 4 remote from the shank 2, is an upright laterally movable supporting member here shown in the form of a flat metal plate 6 having a pair of notches in its lower edge whereby to provide a number of upright legs 7, the lower ends of the latter being hinged at 8 to the head 4 of the base 1, whereby the plate or member 6 may be rocked laterally toward and away from the saw S. To accomplish this adjustment of the member 6, the central leg thereof is provided with an ear 9 which depends below the head 4 of the base 1 and receives the threaded end of a manually operable adjusting screw 10, the latter being extended transversely beneath the portions 2 and 4 of the base and being swiveled at 11 in one of the feet of the shank 2. By this construction, it will be seen that manual adjustment of the screw 10 will rock the supporting member 6 toward or away from the saw as the case may be, thus allowing a very accurate adjustment to be made when the base has been securely clamped in position upon the saw table.

In the present embodiment of the invention, the upper edge portion of the plate 6, is shown as provided with a pair of alined bearings 12 which constitute a guideway in which a reciprocatory rod 13 is slidably supported, this rod being here shown as constructed of a main section 13^a and a supplemental section 13^b hinged to one end thereof to swing laterally. Such movement is imparted to the section 13^b, by practically any preferred type of cam 14, this cam being here shown in the form of a plate having a groove 14^a in its upper side extending substantially throughout its length, and an additional groove 14^b lying parallel to approximately half of said groove 14^a and communicating therewith at one end as seen at 14^c, communication between the groove 14^a and the other end of the groove 14^b, however, being prevented by a flat leaf spring or tongue 14^d which spans this end of the groove 14^b, all of these details being most clearly disclosed in Fig. 5. Depending from the section 13^b of the bar 13, is a pin 15, which, when said bar is being shifted in one direction upon the working stroke of the file, travels throughout the length of the groove 14^a thus holding the two sections 13^a and 13^b in alinement and retaining the

file in contact with the saw. Upon the end of this working stroke, however, the pin travels around 14^a into the groove 14^b, thus moving the movable section 13^b laterally to 5 the dotted line position shown in Fig. 4 to thereby dispose the file out of contact with the saw. Upon the return stroke of the bar 13 and the file, the pin 15 travels within the groove 14^b until it comes into contact 10 with the spring 14^a whereupon this spring yields and allows the pin to again enter the groove 14^a, thus again forcing the file into contact with the saw in position for the next working stroke of said file. Upon such 15 return stroke of the file and parts actuating the same, the saw S is shifted upwardly a distance equal to the length of one tooth, thus disposing an unfiled tooth to be acted upon by the file upon its next working 20 stroke. This shifting of the saw is accomplished by an intermittent feed mechanism to be hereinafter described.

Although the bar 16 might well be connected to the rod 13 by practically any preferred means, the opposite ends of this rod 25 are preferably provided with upright posts 18, to the upper ends of which the opposite ends of said bar are pivoted as seen at 19. Furthermore, although any preferred means 30 could be employed for securing the file 17 in operative relation to the bar 16, a pair of spaced nuts 20 having clamping screws 21 threaded inwardly therethrough, is preferably provided, these nuts having clamp- 35 ing yokes 20^a slidable longitudinally upon the bar 16 and releasably secured in position by set screws 22 or the equivalent thereof. In the present embodiment of the invention, the inner facing ends of the set 40 screws 21 are shown as provided with sockets 23 which receive the opposite ends of the file 17 and thus securely clamp the same in position. The socket of one screw is of triangular formation, if the file be of such 45 shape, and this screw is provided with any preferred means for releasably locking it against rotation, this means being here shown in the form of a set screw 24.

From the preceding description, it will 50 be evident that as the rod 13 is reciprocated and its movable section 13^b is shifted laterally upon each stroke, one end of the bar 16 is likewise shifted laterally, thus moving the file away from the saw on its return 55 stroke, and projecting said file against the saw on its working stroke.

It often becomes expedient to shorten or 60 lengthen the working stroke of the file 17 according to the character of the work being done, and since means to be described is provided for varying the stroke of the rod 13, it becomes highly essential to so mount the cam 14 as to allow it to be adjusted longitudinally of said rod, thus allowing the point at which the file is re-

tracted from the saw to be readily under control of the operator. Numerous details of construction may be provided for accomplishing this result, but as typical of one very efficient style of construction for so 70 doing, we have shown the cam 14 resting upon a cam carrying plate 25 which projects laterally from the plate 6, said cam being adjustably secured to the two plates 6 and 25 by two or more screws 26. It will thus 75 be evident that by removing these screws the cam may be shifted longitudinally, thus allowing the desirable results above mentioned to be attained.

For the purpose of reciprocating the rod 80 13 and the parts carried thereby, an upright lever 30 is fulcrumed at its lower end to the base as seen at 31, while its upper end is provided with a slot receiving a pin 32 which projects laterally from said rod, 85 the lower end portion of the lever 30 being provided with an upright series of openings 33 through one of which a screw 34 is removably passed, this screw being likewise passed through one end of a pit- 90 man 35, which end may therefore be adjusted vertically by removing the screw and inserting it through another opening 33. The other end of the pitman 35 is pivotally connected to the crank 36 of the crank shaft 95 37, the latter being rotatably mounted in bearings carried by the upper ends of posts 38 which rise from one end of the head 4 of the base 1. Although any preferred means may be provided for rotating the 100 shaft 37, a pulley 39 is shown as secured thereto, whereby a driven belt may be applied for driving said shaft, thereby reciprocating the pitman 35 and oscillating the lever 30, the latter now imparting reciprocatory movement to the rod 13 and the parts carried thereby. It is to be observed that due to the fact that the pitman 35 is connected to the lever 30 near the lower end thereof, only a very small amount of movement need be imparted to said pitman in order to shift the rod 13 the necessary amount, this being of course due to the fact that the upper end of said lever 30 moves a greater distance than the portion thereof 110 115 near its fulcrum.

In addition to the parts above described, the rear side of the plate 6 is provided with an upright flange 40 which abuts one flat side of the saw S when the machine is applied to use. Immediately to one side of the flange 40, the plate 6 is slotted as seen at 41, and an oscillatory arm 42 which is pivoted to ears 43 on the front side of the plate 6, is projected rearwardly through said slot. The rear projecting end of the oscillatory arm 42 is provided with a pivotally mounted dog 44 which engages the teeth of the saw S and lifts the same upwardly, after the arm 42 is raised by most 120 125 130 135 140 145 150 155 160 165 170 175 180

any preferred means. In the present case, however, a vertically adjustable horizontal lever 45 and a cam 46 for rocking the same, is shown for the purpose of raising the arm 42 at the proper time. As clearly shown in Fig. 5, one end of the lever 45 underlies the arm 42, while the other end thereof is disposed beneath the cam 46 which is carried by one end of the crank shaft 37. The 10 position of parts is such as to move the arm 42 and dog 44 upwardly when the file 17 is being returned to the point at which it starts its working stroke, during which movement said file is spaced from the saw, 15 it being therefore evident that the latter is moved upwardly a distance equal to the length of one tooth, on the inactive stroke of the file, and that it is therefore in position for the file to engage a new tooth, upon 20 its next working stroke.

If the saw teeth be fine, it would of course be undesirable to allow the dog 44 to have an amount of movement greater than the length of the teeth, since were such the 25 fact the saw would be shifted too far upon each stroke of the file. It therefore becomes highly desirable to provide simple and efficient means for limiting the downward movement of the arm 42 and dog 44, 30 thus preventing the undesirable results from being obtained. For accomplishing this end, although practically any type of stop means could be provided, the set screw 47 is preferably provided, the latter 35 being threaded upwardly through a web which connects the lower edges of the ears 43 as shown clearly in Fig. 8.

From the foregoing description, taken in connection with the accompanying drawings, it will be evident that although comparatively simple construction has been provided for carrying out the objects of the invention, the machine will be very efficient in operation and will possess a number of 45 advantageous features.

In the drawings, we have shown a number of specific details for accomplishing probably the best results, and in the foregoing, have described such details, but we 50 need not be limited thereto otherwise than as set forth in the appended claims, it being evident that numerous minor changes in shape, size, etc., may be resorted to without departing from the spirit or sacrificing any of the advantages of the invention as claimed.

We claim:—

1. A saw filing machine comprising a base, a laterally shiftable member rising therefrom, the base being constructed to dispose the toothed edge of a saw in front of said member, a saw filing mechanism carried by said member, and manually operable adjusting means for regulating the position 60 of said member to move the saw filing mech-

anism toward or away from the toothed edge of the saw.

2. A saw filing machine comprising a longitudinally reciprocated laterally shiftable member, saw filing means carried thereby, a cam controlling the lateral shifting of said member and shiftable longitudinally thereof, and means for normally holding said cam against movement.

3. A saw filing machine comprising a guideway and a cam attaching plate adjacent the same, a longitudinally reciprocated member mounted in the guideway and including a laterally shiftable element having saw filing means thereon, and a cam secured 30 to the cam attaching plate for controlling the shifting of the aforesaid element and adjustable longitudinally of said element.

4. A saw filing machine comprising a base, a supporting member rising therefrom, a reciprocated carriage member mounted on the aforesaid member above the base, saw filing means carried by the carriage member, an upright lever fulcrumed at its lower end and having a sliding connection with the carriage member at its upper end, a pitman pivoted to said lever near the lower end thereof, and means reciprocating said pitman.

5. A saw filing machine comprising a base, a supporting member rising therefrom, a reciprocating carriage member mounted on the aforesaid member above the base, saw filing means carried by the carriage member, an upright lever fulcrumed at its lower end 100 and having a sliding connection with the carriage member at its upper end, a pitman pivoted to said lever near the lower end thereof and adjustable vertically thereon, and means reciprocating said pitman. 105

6. The combination with a reciprocating laterally shiftable member, means for reciprocating said member including means whereby the length of the reciprocation may be varied, and saw filing means carried by 110 said member, of a cam controlling the lateral shifting of the latter and adjustable longitudinally thereof.

7. A saw filing machine comprising a supporting member, a guideway carried thereby, a reciprocating rod slidable in said guideway and formed of a pair of hingedly connected sections, means shifting one of said sections laterally as the rod reciprocates, a file carrying member having a pivotal connection with each of said sections, 115 and a file carried by said member.

8. A saw filing machine comprising a supporting member, a guideway carried thereby, a reciprocating rod slidable in said 125 guideway and formed of a pair of hingedly connected sections, means shifting one of said sections laterally as the rod reciprocates, a file carrying bar disposed substantially parallel to the rod and having its two ends 130

4
pivotally connected with the two sections thereof respectively, and a file carried by said bar.

9. A saw filing machine including a cam plate having in one of its sides a comparatively long groove and a shorter groove lying parallel to a portion of the aforesaid grooves, the two grooves being in communication at one end, the other end of the shorter groove being curved laterally to the longer groove, a spring tongue normally closing the laterally curved end of the shorter groove, a pin

disposed for reciprocation in the two grooves, and a reciprocatory laterally shift-
able file carriage carrying said pin. 13

In testimony whereof we have hereunto set our hands in presence of two subscribing witnesses.
